AUTOMATIC VALVE CONTROL MEANS

William O. Martin, Fort Smith, Ark., assignor to
 William O. Martin, Inc., Fort Smith, Ark., a
 corporation of Arkansas

Application March 12, 1945, Serial No. 582,339

4 Claims. (Cl. 171—97)

1

My invention relates to means for automatically operating valves and the like at predetermined distances of travel—instead of at predetermined periods of time—of a vehicle equipped with my means; the invention being especially designed to operate the blow-off cocks of a steam locomotive and to operate or control the valves in the cleaning medium supply lines of the locomotive flue blowers.

My invention has for its object the provision of means whereby the blow-off cocks and the flue blowers of a locomotive will be automatically operated after the locomotive has traveled a preselected distance and is traveling at or above a predetermined speed.

As is well known, in order to obtain efficient and safe locomotive operation, it is essential periodically while the locomotive is in operation to open the blow-off cocks momentarily for the purpose of discharging the accumulated sludge or sediment from the bottom of the locomotive boiler, an operation which at present is manually controlled and therefore depends on the thoughtfulness of the engine crew.

Furthermore, the efficiency and operating cost of a steam locomotive depends greatly on the clean condition of the heat transmitting surfaces—namely the flues and flue sheet of the boiler—obtainable by suitable operation of the flue blowers on locomotives equipped therewith; an operation likewise manually controlled at present and depending, therefore, on the engine crew.

My invention is designed to supplement the manual operation or control mechanism and to provide means designed to automatically perform the functions mentioned, after certain preselected distances of locomotive travel and while the locomotive is operating at or above a predetermined speed, through the operation of electric—or other suitable medium—controlled valves.

The objects and advantages of my invention will be readily comprehended from the following detailed description of the accompanying drawings wherein—

Figure 1 is a diagrammatic view of the rear or firebox end of a locomotive boiler with schematic illustration of blow-off cock, flue blower, main air reservoir, turbo-generator, water column, and current conducting lead lines.

Figure 2 is a plan view of the blow-off cock and flue blower current control mechanism, with the top of the housing removed.

Figure 3 is a side elevational view of said housing and mechanism with the lead lines omitted.

Figure 4 is a detail view of the blow-off cock control mechanism.

2

Figure 5 is a detail view of the flue-blower control mechanism.

Figure 6 is a detail view of a governor type switch control and master switch.

5 My improved means, as previously stated, is especially adapted for use with a moving vehicle and involves a source of electric current and a circuit, a pair of shafts, one of which is rotated, through the medium of gear mechanism of predetermined speed ratio, by a wheel or axle of the vehicle; the second shaft being provided with a plurality of prearranged cams of given formation and arrangement; levers with prearranged cam contacting surfaces, said levers having operative relation with a plurality of secondary switches to affect circuits for controlling desired operations after the vehicle has travelled preselected distances and the first mentioned shaft is revolving at or above a predetermined speed 10 adapted to control a master switch which controls the circuits of the secondary switches.

As is well known, in order to obtain efficient and safe locomotive operation, it is essential periodically while the locomotive is in operation to open the blow-off cocks momentarily for the purpose of discharging the accumulated sludge or sediment from the bottom of the locomotive boiler, an operation which at present is manually controlled and therefore depends on the thoughtfulness of the engine crew.

My improved means is designed to provide one or more automatic operations where such operations are desired to be performed from a distance 15 stand point; that is to say, after the power imparting element has revolved a predetermined number of revolutions and reached a preselected speed corresponding to a predetermined distance of travel, at which time it is desired that said operation or operations be intermittently performed.

As an exemplification of the adaptation of my invention, I illustrate its application to a locomotive and the operation of its blow-off cocks and flue blowers.

My means, as exemplified in the drawings, is especially designed for the automatic operation of the blow-off cocks of a locomotive and of the flue blowers, where the locomotive is equipped with 20 such blowers.

In proper locomotive operation, it is essential to periodically open the blow-off cocks while the locomotive is in operation for the purpose of blowing off the accumulated sediment in the boiler. This operation is intended to be performed by the locomotive crew during given distances of locomotive travel in order to obtain safe and efficient operation. Where the locomotive is equipped with flue blowers, it is also desirable 25 that the locomotive crew place the blowers in operation after the locomotive has traveled given distances, for the purpose of removing the accumulated soot and cinders, which impair the heat transmitting efficiency of the flues and flue sheet of the boiler.

In present day practice, both of these opera-

tions depend on the thoughtfulness of the locomotive crew and the performance of the operations after the locomotive has traveled certain distances.

My improved means is designed to eliminate the human factor and to provide these operations after the locomotive has traveled a preselected distance and is traveling at not less than a given speed so as not to reduce the steam pressure or operating efficiency while the locomotive is laboring under a heavy load or hard pull.

It is also essential that these operations be controlled by the speed of locomotive travel rather than the element of time so that these operations cannot be performed at improper moments, as for example while arriving at or while the locomotive is standing in a station.

My improved means has been designed to eliminate these objectionable possibilities and in the particular embodiment disclosed consists of a suitable enclosure or housing 25 adapted to be mounted on the locomotive underframe in proximity to one of the locomotive wheels or on the ends of an axle. Mounted on one of the housing walls, preferably on the exterior, is a drive wheel 26 which may be frictionally rotated through contact with a locomotive wheel; the drive wheel preferably being of predetermined diameter. Rotatably mounted in the housing are a pair of main shafts 27 and 28 which are adapted to be rotated at predetermined speeds controlled by gear mechanism of a predetermined speed ratio whereby the shaft 28 is given one rotation after shaft 27 has had a predetermined number of revolutions, corresponding to a preselected distance of travel by the locomotive. The gear mechanism illustrated involves a pinion 29 mounted on the stub-shaft of the drive wheel 26 and meshing with gear 30 mounted on shaft 27, which is provided with a gear 31 meshing with a gear 32. Gear 32 drives a worm 33 which drives worm gear 34 secured to a worm 35 which in turn rotates worm gear 36 secured to shaft 28.

As the exemplification is designed for the periodical operation of the blow-off cocks at opposite sides of the locomotive and also alternate operation of a pair of flue blowers mounted at opposite sides of the locomotive fire-box, the shaft 28 is shown provided with a multiple of radially disposed cam action members arranged to come into operative position during predetermined degrees of rotation of said shaft 28, in order that the operation of the blow-off cocks at opposite sides of the locomotive do not take place simultaneously and that the operations of both flue blowers do not occur at the same time nor at the time of operation of the blow-off cocks, as the simultaneous operation of the blow-off cocks and of the flue blowers, not only would place too difficult a task on the general electric circuit (also used for operation of other devices) but would also result in too great a reduction in steam pressure for the normal operation of the locomotive under certain conditions.

As previously stated, main shaft 28 is designed to make one revolution in a predetermined distance of locomotive travel, during which period the blow-off cocks are intended to be twice alternately operated; that is to say the blow-off cocks are to be operated during each half revolution of shaft 28, or during one half the preselected distance of locomotive travel; while the flue blowers are intended to be alternately operated at the completion of each single revolution of the main shaft 28. Therefore, shaft 28 is shown

provided with a pair of cam members 37, 37^a, fixedly secured to shaft 28 to extend radially to opposite sides of the shaft 28, as shown in Figure 3, thus causing blow-off operations during each half revolution of shaft 28. As locomotive blow-off operations generally consist of a number of momentary or short openings of the blow-off valves, the outer ends of the cam members 37, 37^a are each shown provided with a plurality of contact points 38, for example three as shown in Figure 3, with the corresponding cam members 37^a offset circumferentially a slight degree from the first mentioned cam member 37 in order to stagger the respective contact points of the two cam members and thereby cause alternate operation of the blow-off cocks at opposite sides of the locomotive.

Pivotedly mounted adjacent the cam members 37 and 37^a are pivotally mounted levers 39 and 39^a, each provided with an offset portion or lug 39^b with which the cam points 38 are adapted to contact and cause oscillation of the levers which automatically are adapted to return to normal position, through the usual springs in the secondary switches with their respective lugs 39^b disposed in the path of the cam points 38.

Arranged adjacent the free end of each lever 39 and 39^a and to be actuated thereby is a plunger 40 of an electric spring switch 40^a whose spring not only returns the switch to open position as soon as pressure is released, but also may be employed to move the levers 39, 39^a back to normal position.

With the construction shown, the forward point 38 of cam 37 will contact lug 39^b and force lever 39 and its associated plunger switch 40^a into switch closing position until the cam point moves past lug 39^b of the lever, at which time the lever 39 will return to normal position and the plunger switch will return to open position. The foremost point 38 of cam 37^a will then contact the lug 39^b of its associated lever 39^a and perform a similar operation; after which the second and then the third cam points 38 of cams 37 and 37^a will successively come into play and thereby provide repeated alternate operations of levers 39 and 39^a and their associated switches.

As the exemplification also is designed for a locomotive provided with a pair of flue blowers (one at each side of the firebox) the shaft 28 is shown provided with a pair of cams 41, 41^a, adapted to come into play at the completion of each revolution of shaft 28; the cams 41, 41^a being suitably spaced and preferably circumferentially offset a predetermined degree so as to successively come into operative position. Pivotedly mounted adjacent the paths of cams 41 and 41^a are levers 42, 42^a; and each lever is provided with an offset portion or arcuate lug 42^b of predetermined size or width, lengthwise of the lever, so as to remain in operative contact with the cam 41, or 41^a, for a predetermined period of time during rotation of shaft 28. The free end of each lever 42, 42^a is adapted to contact its respective spring controlled, normally open, plunger switch 43^a; that is to say, lever 42^a is adapted to actuate its associated switch 43^a after lever 42 and its associated switch 43 have returned to normal position.

The housing 25, adjacent the end of shaft 27, is provided with an electric switch, preferably of the spring controlled self opening type, indicated at 44, (which may be termed master switch in so far as this mechanism is concerned—hence not the main hand operated switch in the cab of

the locomotive) intended to be connected with an electric or current supply line 44^a which is arranged in electric relation with the current generator 45, or other suitable source of electric current supply. This so-called master switch 44 is arranged in a normally open electric circuit which involves the lines or wires indicated at 46, connected with the secondary or plunger switches 40^a, 40^b and 43^a, 43^b; and the secondary or plunger switches in turn in this exemplification are connected or wired to solenoid valves arranged in the air lines adapted to operate the respective blow-off cocks and flue blowers.

The spring controlled button or plunger of the so-called master switch 44 is controlled by the weighted levers or arms of a suitable governor indicated at 47. The governor, which is secured on shaft 27 to rotate therewith, is adapted to function when the centrifugal force—induced by rotation of the shaft and governor at or above a preselected speed—is sufficient to overcome the friction of the plunger and the predetermined spring pressure of the master switch button; the switch being intended to return to normal open position as soon as the speed of shaft 27 and the governor 47 drops below the preselected speed and releases pressure on the plunger or pressure member.

When the master switch 44 is closed, the electrical energy is available at the respective secondary or control switches. The electrical energy is taken from the master switch 44 by means of wires 46 arranged in a conduit 46^a which is connected with the switch box containing the control or secondary switches; with the outgoing wires 46 from the switch box leading to various points of operation.

In the exemplification, secondary switch 40^a, controlled by lever 39 is connected with the solenoid valve 49 in the air line 51, leading from the main air reservoir 52 to the blow-off cocks 53 on the adjacent side of the locomotive; and the secondary switch 40^b controlled by lever 39^a is likewise connected with a solenoid valve 49 in an air line leading to the blow-off cock or valve on the opposite side of the locomotive.

As previously stated, blow-off valves or cocks in railroad practice are momentarily and alternately operated. In my automatic means this is accomplished by the prearranged type of lugs 39^b on levers 39 and 39^a and the staggered relation of the projections 38 on the cams 37 and 37^a, causing alternate operation, from right to left to right to left, etc., which, in this particular exemplification, results in three momentary operations of each blow-off cock in alternating sequence during each ten mile (or approximately) travel of the locomotive.

As the gear mechanism shown is intended to produce one complete revolution of shaft 28 after drive wheel 26 has revolved a predetermined number of times—namely in this instance after the locomotive is supposed to have traveled approximately twenty miles, the cams 37, 37^a (arranged to extend to opposite sides of shaft 28) will produce two complete blow-off operations during one revolution of shaft 28, namely during approximately each twenty miles travel of the locomotive, namely a blow-off during each ten miles of travel.

With the secondary or control switches 40^a in a normally inactive or open circuit, operation of the switches 40^a by the cams 37, 37^a will be ineffective unless shaft 27 is rotating at or above the preselected speed designed to actuate the gov-

ernor 47 sufficiently to overcome the prearranged resistance and spring pressure of the so-called master switch operating plunger 44, thereby closing said switch and establishing communication between the source of current supply and said secondary or control switches. That is to say, the blow-off operations will not take place unless the locomotive is traveling at or above twenty miles an hour, in order that the steam pressure be not reduced while the locomotive is climbing a grade or laboring under a hard pull, or while slowly moving into a station.

As the flue blowing operations need not be as frequently performed, the flue blower secondary switches 43^a and controlling levers 42, 42^a are arranged to alternately provide one operation of each flue blower during a complete rotation of the shaft 28, namely after the locomotive has traveled approximately twenty miles; and in view of the nature of this operation, the bulges or lugs 42^b of levers 42, 42^a are somewhat enlarged to hold the respective switches 43^a in closed condition for a sufficient length of time, namely while the locomotive is traveling, for example, a distance of approximately one mile.

With my improved means as heretofore described, automatic operations of the blow-off cocks or of the blowers will not take place regardless of whether the cams are in contact with the respective switch operating levers in what may be termed "on" position until the speed of the locomotive is at or above the predetermined speed of say twenty miles an hour or over, thus preventing operations at inopportune moments. Although my improved means is especially adapted for the operations mentioned, it is apparent that said means may be employed for a number of automatic operations where the operations are to be performed from a standpoint of distance or at certain speeds instead of from a time element standpoint.

I have shown and described my improved means as especially adapted for the automatic operation, by a suitable medium such as electricity, of the blow-off cocks and the flue blowers of a locomotive, but it is apparent that the invention may be employed for the automatic operation of valves or other elements which are to be operated during certain speed or distance conditions rather than at certain definite periods of times. Furthermore the mechanism within the housing unit may be driven indirectly from a locomotive or tender axle or wheel or remote control drive means may be employed and/or mechanically equivalent means, instead of gears, may be employed for rotating the shafts in the housing; and while the exemplification is believed to be a suitable embodiment of the invention, certain structural modifications and circuit arrangements may be possible without, however, departing from the spirit of my invention as defined in the appended claims.

What I claim is:

1. In automatic mechanical control means of the character described, the combination of a locomotive provided with a source of current supply and an electric circuit; a drive wheel of predetermined diameter adapted to rotate at the speed of one of the wheels or axles of the locomotive; a pair of rotatable shafts, one of said shafts being driven by said drive wheel through the medium of gear mechanism of predetermined gear ratio, said shaft being provided with a governor controlled plunger; a normally open master switch in said circuit adapted to be closed by

said governor controlled plunger whereby the master switch is closed when the locomotive is traveling at or above a predetermined speed; a train of gears of predetermined ratio operatively intermediate said rotatable shafts whereby the second of said pair of shafts is given one rotation when the locomotive has traveled a prearranged distance; said last mentioned shaft being provided with a plurality of radially disposed and laterally spaced cams arranged at predetermined degrees apart with certain of the cams coming into operative position at completion of each revolution of said second shaft while the other cams arrive at operative position during each half revolution of said shaft and are provided with spaced operating surfaces and said cams brought into operative positions when the locomotive has traveled a predetermined distance; levers pivotally mounted adjacent said second shaft and provided with cam engaging surfaces of prearranged dimensions whereby the length of time of lever movement is controlled; a plurality of switches adapted to be actuated by said levers when the locomotive has traveled a predetermined distance and is traveling at or above a predetermined speed, said last mentioned switch being energized when said master switch is closed.

2. In automatic mechanical means for closing certain normally open electric circuits at predetermined distances and speed of travel of a vehicle, in combination with a vehicle provided with an electric current supply, an electric circuit with a master switch, a driving member adapted to rotate at the speed of rotation of a vehicle wheel or axle; a pair of rotatable shafts, one of said shafts being provided with a plurality of longitudinally and circumferentially spaced radially disposed cams, certain of said cams being adapted to come into operative position during each half revolution of said shaft, while the other cams are adapted to come into operative position at completion of each complete revolution of said shaft; a plurality of secondary circuit controlling switches; a plurality of levers for successively operating said switches, said levers being tiltably mounted in the paths of said cams and to be operated thereby; gearing operatively intermediate the driving member and the other of said pair of shafts whereby the latter is given a predetermined number of revolutions during a prearranged distance of vehicle travel; and a governor controlled member operatively associated with the last mentioned shaft and adapted to operate said master switch whereby the secondary circuits are energized after the locomotive has traveled a prearranged distance and is traveling at or above a predetermined speed.

3. In automatic means for controlling normally open electric switches on a locomotive; a drive wheel adapted to be rotated by and substantially at the speed of a rotating axle or wheel of the locomotive; a housing secured in proximity to the locomotive axle or wheel; a pair of rotatable shafts mounted in said housing; driving mechanism intermediate said drive wheel and one of said shafts for rotating the latter at a prearranged speed and constituting the drive shaft; an electric circuit provided with a normally open master switch connected with a source of electric current supply and a plurality of normally open secondary switches; gear mechanism interme-

diate the drive shaft and the other of said pair of shafts; a governor controlled plunger slidably arranged on said drive shaft whereby the master switch is closed when the locomotive and said drive wheel are traveling at or above a predetermined speed; a plurality of cam members, secured on the second mentioned shaft, provided with a prearranged number of radially projecting contact surfaces, with the actuating surfaces of one set of cam members circumferentially staggered with those of the other set of cam members; a pivoted lever operatively intermediate each cam member and each secondary switch adapted to be successively operated by said contact surfaces during each complete rotation of said cam shaft for prearranged periods of time, said levers being adapted to return to normal position when the cams move out of operative position; the speed ratio of said drive mechanism intermediate the drive wheel and the drive shaft and between said shafts being such that the cam carrying shaft is given one rotation while the governor carrying or drive shaft has made a predetermined number of rotations, thereby causing the levers to be alternately actuated when the locomotive has traveled predetermined distances and while the locomotive is traveling at or above a predetermined speed.
